CLAIM

The ornamental design for a dosage dispenser for powder, as shown and described.

DESCRIPTION

FIG. 1 is a front perspective view of a dosage dispenser for powder showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the equal length broken lines depict portions of the dosage dispenser for powder that form no part of the claimed design.

1 Claim, 5 Drawing Sheets
